UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

BLINDSTITCH SEWING-MACHINE.

1,132,965.

Specification of Letters Patent. Patented Mar. 23, 1915.

Application filed December 6, 1907. Serial No. 405,356.

To all whom it may concern:

Be it known that I, LANSING ONDERDONK, a citizen of the United States, residing at New York, in the county of New York, 5 State of New York, have invented certain new and useful Improvements in Blind-stitch Sewing-Machines, (Case C,) of which the following is a description, reference being had to the accompanying drawing, and 10 to the letters and figures of reference marked thereon.

My invention relates to new and useful improvements in blind stitch sewing machines, and has for its object to provide 15 means for properly holding and guiding the material to the stitching mechanism.

A further object of my invention is to provide means for properly guiding the needle so as to prevent all undue lateral vibration thereof.

Still further objects of my invention will in part be obvious and will in part be more fully hereinafter pointed out.

In the drawings, which show by way of 25 illustration one embodiment of my invention; Figure 1 is a front elevation of a sewing machine embodying my invention, with certain parts omitted and broken away for the sake of clearness. Fig. 2 is a similar 30 view taken from the rear of the machine. Fig. 3 is a detail sectional view showing the needle lever stud and also the manner in which the presser members are mounted thereon. Fig. 4 is a detail view in end elevation of the work support and the presser 35 members. Fig. 5 is a detail view showing the presser member and the needle groove therein. Fig. 6 is a detail view partly in section showing a slightly modified form of 40 guide groove for the needle. Fig. 7 is a detail view showing a modified form of presser supporting shank.

The work support 1, carries a ridge forming member 2 having formed therewith feeding surfaces 3, 3. The overhanging arm 4 is provided with a bearing in which is mounted a stud 6, which is tapered as shown in Fig. 3 of the drawing, and extends outwardly at each side of said bearing. The collar 7, surrounds the stud and a nut 8 threaded on said stud, firmly holds the stud in its bearing.

Between the nut 8 and the frame of the 55 machine, are mounted two collars 9 and 10. The collar 9 is provided with an outwardly

and downwardly extending arm 11, which carries a presser member 12, at its lower end. The collar 10 is also provided with an outwardly and downwardly extending arm 13 which carries a presser member 14, at its 60 lower end. A spring 15, mounted on a pin 16 at its upper end, engages the arm 11 which supports the presser member 12, and holds the same yieldingly against the side of the ridge crimping member 2. The adjustable thumb screw 17, carried by the lug 18 engages the spring 15 between its ends, and by adjusting said screw, the tension on 65 said spring may be varied.

A stop nut 19 serves to lock the adjustable 70 screw in its adjusted positions. The spring 20 carried by the pin 21 at its upper end, engages the arm 13, which supports the presser member 14. An adjustable screw 22 carried by a lug 23, engages said spring between its 75 ends, and serves as a means for varying the tension of said spring. The stop nut 24, serves as a means for locking the adjusting screw in its adjusted position.

Located intermediate the arms 11 and 13, 80 is a shaft 25 which carries at its forward end a hand lever 26. The shaft 25 carries at its rear end a cam member 27, which is located in the plane of the arms 11 and 13. When the lever 26 is turned by hand, the 85 cam portions of the cam 27, engage the arms 11 and 13 and separate the same, thus, moving the presser members from the ridge forming member.

The presser members 12 and 14 are preferably so located when in closed position, that they are spaced sufficiently to allow the material to be pressed up between the same by means of the crimping ridge. I have provided a stop pin 28 which limits the 95 inward movement of the presser members when there is no material in the machine. The work support 1 is raised and lowered for the insertion of the material by any suitable means.

The needle 29 is carried by a needle lever 30, which is mounted on the forwardly projecting portion of the stud 6. It will therefore, be seen that the axis about which the needle oscillates, co-incides with the axis 105 about which the presser members swing. The work support, when raised to its normal position for operation is held rigidly and therefore, as the work passing through the machine varies in thickness the presser 1

members 12 and 14 will be gradually moved back and forth.

The presser member 14 is preferably provided with a needle guiding groove 31 and 5 the needle is so located as to engage said needle guiding groove, and the needle is therefore held under slight tension or strain. It is very essential therefore, that the presser member 14 shall have a definite position 10 relative to the needle path.

By mounting the presser member on an axis co-incident with the needle lever, it will be seen that the presser member, regardless of its position, will retain a definite position 15 relative to the needle.

The needle is oscillated by means of a link 32 in any suitable manner. Co-operating with said needle, I preferably use a thread carrying looper and spreader, such 20 as shown in my co-pending application Serial No. 405,359, filed of even date here-with, although any other form of comple- 25 mental stitch forming mechanism may be used without in any way departing from the spirit of my invention.

The presser member 14 is cut away so as to give clearance to the needle.

In Fig. 6, I have shown the clearance groove in the presser foot as formed on substantially the same arc as the arc of a needle. By cutting the groove in the presser foot in this manner, I cut away as little material as possible and furthermore, form a better supporting surface for the needle.

In Fig. 7, I have shown the shank of the presser foot as extending down below the stitching point and the presser foot curved, as at 14', substantially on the same arc as the crimping rib so that the material after 40 passing the stitching point will be deflected downward and properly held relative to the crimping member and work support. It will also be noted from this figure that the front portion of the work support extends 45 upward above the stitching point, so that the material may be readily inserted beneath the presser foot.

Having thus particularly described my invention, what I claim as new and desire to 50 secure by Letters Patent, is:—

1. The combination with an overhanging arm, a curved needle, means for oscillating the same, a work support, a crimping ridge carried thereby, presser members piv- 55 oted so as to swing independently on an axis fixed relative to the overhanging arm and coincident with the axis of the needle, and means for swinging the presser members on said axis.

2. The combination with a work support having means for crimping the fabric, a curved needle, means for oscillating said needle, and a plurality of oppositely dis- 60 posed presser members, each of which is

mounted on an axis coincident with the axis 65 of the needle, said presser members operating to hold the material on the work support against the crimping means.

3. The combination of a curved needle, a needle lever, supporting the same, a work 70 support, a crimping ridge carried thereby and presser members each of which is piv- 75 oted on an axis co-incident with the axis of the needle lever, said presser members being disposed on opposite sides of said crimping ridge.

4. The combination of a curved needle, a needle lever supporting the same, a work support, a crimping ridge carried thereby, presser members each of which is pivoted 80 on an axis co-incident with the axis of the needle lever, said presser members being dis- 85 posed on opposite sides of said crimping ridge, means for yieldingly holding said presser members in engagement with the crimping ridge.

5. The combination of a work support, a crimping ridge carried thereby, an over- 90 hanging arm, a needle lever pivoted thereon, a needle carried by said needle lever and 95 presser members, each of which is pivoted on an axis co-incident with the axis of the needle lever, said presser members being dis- posed on opposite sides of said crimping ridge. 95

6. The combination of a work support, a crimping ridge carried thereby, an over- 100 hanging arm, a needle lever pivoted thereon, a needle carried by said needle lever and 105 presser members pivoted on an axis co-inci- 100 dent with the axis of the needle lever, said presser members being disposed on opposite sides of said crimping ridge, means for yieldingly holding said presser members in engagement with the crimping ridge and 105 means for separating said presser members.

7. The combination with a work support, a crimping ridge carried thereby, an over- 110 hanging arm having a reduced portion at the lower end of its head, a stud passing 110 through said reduced portion and clamped therein, a needle lever pivoted on said stud on one side of said reduced member, a 115 needle carried thereby, and a presser member pivoted on said stud on the other side of said reduced member, and means for holding said presser member in contact with said crimping ridge.

8. The combination with a work support, a crimping ridge carried thereby, an over- 120 hanging arm having a reduced portion at the lower end of its head, a stud passing 120 through said reduced portion and clamped therein, a needle lever pivoted on said stud on one side of said reduced member, a 125 needle carried thereby, and a plurality of presser members mounted on said stud on the other side of said reduced member and

cooperating to hold the work upon said crimping ridge, and means for separating said presser members.

9. The combination with a work support, 5 a crimping ridge carried thereby, an overhanging arm, a needle lever pivoted on said overhanging arm, a needle carried thereby, a pair of presser members each of which is pivoted on an axis co-incident with the axis 10 of said needle, said presser members being located one on each side of the crimping ridge, and means for holding said presser members in contact with said crimping ridge.

15 10. The combination with a work support, a crimping ridge carried thereby, an overhanging arm, a needle lever pivoted on said overhanging arm, a needle carried thereby, a pair of presser members pivoted 20 on an axis co-incident with the axis of said needle, said presser members being located one on each side of the crimping ridge, springs for yieldingly holding said presser members in contact with said crimping ridge 25 and means for separating the presser members.

11. The combination with a work support, a crimping ridge carried thereby, an overhanging arm, a needle lever pivoted on said 30 overhanging arm, a needle carried thereby, a pair of presser members pivoted on an axis co-incident with the axis of said needle, said presser members being located one on each side of the crimping ridge, springs for 35 yieldingly holding said presser members in contact with said crimping ridge, and means for separating the presser members, and means for adjusting the tension on said springs.

40 12. The combination with a work support, a crimping ridge carried thereby, an overhanging arm, a needle lever mounted on said overhanging arm, a needle carried thereby, presser members pivoted on an axis 45 co-incident with the axis of said needle lever, a cam intermediate said presser members for separating the same, and means for operating said cam.

13. The combination with a work support, 50 a crimping ridge carried thereby, an overhanging arm, a needle lever mounted on said overhanging arm, a needle carried thereby, presser members pivoted on an axis co-incident with the axis of said lever, a cam intermediate 55 said presser members for separating the same, means for operating said cam, springs for engaging said presser member, whereby the same are held against the crimping ridge.

60 14. The combination with a work support, of a crimping ridge carried thereby, an overhanging arm, a needle lever mounted on said overhanging arm, a needle carried thereby, presser members pivoted on an axis

co-incident with the axis of said needle lever, a cam intermediate said presser members for separating the same, means for operating said cam, springs for engaging said presser members, whereby the same are held against the crimping ridge, and means 70 for adjusting the tension on said spring.

15. The combination with a work support, of a crimping ridge carried thereby, an overhanging arm, presser members located on opposite sides of the crimping ridge pivoted 75 on a common axis on said overhanging arm so as to swing independently, a needle lever mounted on an axis co-incident to the axis of said presser members, a needle carried by said needle lever, and so disposed that the 80 path of said needle passes over said presser members.

16. The combination with a work support, of a crimping ridge carried thereby, an overhanging arm, a needle lever pivoted on said 85 overhanging arm, a needle carried thereby, presser members movable independently and disposed on opposite sides of the crimping ridge and means for supporting said presser members on an axis coincident with the 90 axis of the needle bar, whereby said presser members retain a constant position relative to the path of said needle regardless of the thickness of the fabric operated upon.

17. The combination of a work support normally rigidly held in operative position, a crimping ridge carried thereby, an overhanging arm, a needle, a needle lever pivoted on said overhanging arm, presser members and means for yieldingly supporting said presser members, whereby the same maintain a constant position relative to the path of the needle, irrespective of the thickness of the fabric operated upon.

18. The combination of a work support, normally held in rigid operative position, a crimping ridge carried thereby, an overhanging arm, a needle lever pivoted on said overhanging arm, a needle carried thereby, 110 presser members located on opposite sides of said crimping ridge pivoted so as to swing independently on an axis co-incident with the axis of the needle lever, means for yieldingly holding said presser members in 115 contact with said crimping ridge, and means for separating said presser members.

19. The combination of a work support normally held in rigid operative position, a crimping ridge carried thereby, an overhanging arm, a needle lever pivoted on said overhanging arm, a needle carried thereby, presser members pivoted on an axis co-incident with the axis of the needle lever, means for yieldingly holding said presser 120 members in contact with the material on said crimping ridge, a cam mounted between said presser members for separating the

same, and a hand lever for operating said cam.

20. The combination of a curved needle, a needle lever supporting the same, a work support, a crimping ridge carried thereby, presser members pivoted on an axis co-incident with the needle lever and means for holding said presser members from pressing on the crimping ridge when there are no goods under said presser members.

21. The combination of a curved needle, a needle lever supporting the same, a work support, a crimping ridge carried thereby, presser members pivoted on an axis co-in-

cident with the axis of the needle lever, means for yieldingly holding said presser members in engagement with the crimping ridge, additional means for holding said presser members from pressing on the crimping ridge when there are no goods under said presser members.

In testimony whereof I affix my signature, in presence of two witnesses.
